Application July 8, 1924, Serial No. 724,762

35 Claims. (Cl. 250—27)

This invention relates to electric wave signaling systems, and more particularly, to means for eliminating the effects of undesired energy variations in such systems.

5 In carrier wave signaling systems, and particularly in radio systems employing space discharge tubes, designed to transmit or receive speech or music, numerous attempts have been made to utilize sources of alternating current for supplying space current, filament heating current and also polarizing potentials to the control electrodes of the tubes of the system. Heretofore, all such attempts have resulted to a greater or lesser degree in the introduction of undesired 10 potential variations into the system tending to adversely affect its stability and also the quality and volume of received signals.

The use of alternating current in radio systems for the purposes described, however, has 20 important advantages in that the circuits may be simplified, the efficiency of operation may be increased, and the cost of construction and operation reduced to a minimum. Batteries for supplying current may be eliminated and ordinary 25 110 or other voltage alternating current used to supply the system.

An object of this invention is to eliminate disturbing effects in radiant energy or other electric 30 wave signaling systems utilizing alternating current sources.

Another object is to prevent the introduction of ripples tending to distort the signals in systems utilizing sources of alternating current.

An additional object is to maintain a uniform 35 potential over the surface of the cathodes of space discharge tubes included in an electric wave signaling system.

A further object is to prevent current flowing 40 in the heating element of space discharge tubes having equipotential cathodes from introducing variations in the potential gradient between the cathodes and anodes of the tube.

Another object is to compensate for inherent 45 leakage between different portions of the apparatus of a radiant energy signaling system, thereby preventing the introduction into the system of undesired energy variations which tend to interfere with the signals.

50 A feature of the invention relates to an arrangement whereby energizing currents and control potentials may be supplied by a single alternating current source to space discharge tubes included in an electric wave signaling system, in such manner that variations of the energy sup-

plied by the source do not cause interference with the signals.

Another feature relates to a signaling system utilizing space discharge tubes, including electron emitting cathodes having means connected 5 between the cathodes and heating elements therefor which maintains a substantially uniform potential over the surfaces of the cathodes.

Another feature relates to a grid filter arranged to prevent variations of current in the output 10 circuit of space discharge tubes from affecting the potential applied to the control electrodes of the tubes.

Broadly, this invention comprises an electric 15 wave translating system utilizing space discharge tubes having cathodes of large surface area which are arranged to be heated by radiation from a heating element such as an incandescent filament.

The system utilizing these tubes, known as 20 equipotential cathode tubes, is arranged to be supplied with energy from a single source of alternating current. The heating elements or filaments of the tubes may be supplied with current from a transformer having its primary winding 25 connected to the source of alternating current. Space current for the tubes is supplied from the source of alternating current through a rectifier and filters. Potential for the control electrodes is provided by the drop of potential along 30 a resistance common to the input and output circuit of the tubes. Filters are included in the circuit for connecting this resistance to the control electrodes of certain tubes of the system 35 to prevent variations of voltage drop across the resistance from being transmitted to the control electrodes.

In order to prevent changes in the drop of potential along the heating element or filament of the tubes from introducing changes in the potential gradient between the cathodes and anodes 40 of the tubes and from producing inequalities in the distribution of potential over the surface of the cathodes, or from producing other effects which would cause variations in the space current 45 flowing through the tubes, a path having low impedance for alternating currents and high impedance for direct currents is provided between the cathodes and filaments of the tubes. This path in one instance may be provided by series 50 condensers having their terminals connected to opposite sides of the filament heating circuit and their mid-point connected to the cathodes. In another instance, the path may be provided by a condenser having one plate connected to the 55

cathodes and its other plate connected to the mid-point of the secondary winding of a transformer supplying current to the heating filaments. This path seems to balance the circuit of the system so that changes in the drop of potential along one-half of the heating filaments are exactly compensated by the changes in the drop of potential along the other half of the filaments. By virtue of this arrangement these changes do not produce, either directly or indirectly, changes in the space current flowing through the tubes and consequently do not detrimentally effect the signals received.

The invention both as to its organization and method of operation to effect the objects noted above, as well as the additional features and objects, will be better understood by reference to the following detailed description taken in connection with the drawings in which:

Fig. 1 illustrates a radio receiving system employing equipotential cathode tubes supplied with energy from a source of alternating current.

Fig. 2 illustrates a slightly different method of connecting the cathodes and heating filaments for preventing ripples in the space current of the tube.

Fig. 3 illustrates one form of the space discharge tubes of Fig. 1.

Fig. 3a is a view in section of the tube electrodes taken on line 3a—3a of Fig. 3.

Fig. 4 illustrates a form of space discharge tube different from that shown in Fig. 3.

Fig. 5 is a transparent perspective view partly in section illustrating a transformer of the system of Fig. 1.

Fig. 6 shows a characteristic curve illustrating the properties of the transformer.

The circuit illustrated in Fig. 1 includes an antenna 10 coupled to high frequency amplifier 20 arranged in tandem with a detector 30 and a low frequency amplifier 40. The amplifier 40 supplies signal currents to a cone type loud speaking receiver 50.

The antenna circuit includes a variable condenser 11 in series with a loading coil 12 and the primary winding of a variable transformer 13 having one terminal connected to ground. The secondary winding of transformer 13 has one terminal connected to the grid of space discharge tube 21 and the opposite terminal connected to the anode of this tube in series with a small adjustable condenser 14. A variable condenser 15 is connected in shunt across the secondary winding to form a resonant circuit therewith. The resonant circuit may be tuned by adjusting this condenser. The antenna circuit may be tuned by adjusting condenser 11.

The tube 21 includes in addition to the grid and anode already mentioned, a cathode 22 and a filament 23.

The input circuit for the tube is connected between the grid and cathode and may be traced as follows: from the grid of the tube, one-half of the secondary winding of transformer 13, the mid-tap of this winding to the grid filter resistance 25 to the cathode 22 and across the space within the tube to the grid.

The alternating current output circuit for tube 21 is connected to the cathode and anode. This circuit may be traced from the anode to primary winding of transformer 26, by-pass condenser 27 to the cathode 22 and across the space within the tube to the anode. A space current circuit for tube 21 is also connected to its anode and cathode and may be traced from the anode, through pri-

mary winding of transformer 26, filter 28, secondary windings 31 and 30' of transformer 32, rectifier 29, resistance 25 to the cathode 22.

The resistance 25 is included in a portion common to both the input circuit of tube 21 and its space current circuit.

The secondary winding of transformer 26 is included in the input circuit of the space discharge tube 36 in series with a blocking condenser 34 shunted by a leak resistance 35. This input circuit is connected to the control electrode and the cathode of tube 36.

The output circuit of tube 36 is connected to the anode and cathode of the tube and includes the primary winding of low frequency transformer 37 in series with by-pass condenser 38 both shunted by a second condenser 39.

The space current path of the tube 36 may be traced from the anode to the primary winding of the transformer 37, filter 41, filter 28, secondary 20 windings 30' and 31 of transformer 32, rectifier 29, resistance 25 to the cathode of the tube.

The secondary winding of the transformer 37 is included in the input circuit of a low frequency amplifier 40. This input circuit may be traced from the grid of tube 42, secondary winding of transformer 37, filter 43, resistance 25 to the cathode of the tube 42. The alternating current output circuit of tube 42 extends from the anode through the primary winding of transformer 45 30 and by-pass condenser 27 to the cathode.

The space current circuit of tube 42 extends from the anode of the tube through the primary winding of transformer 45, filter 28, windings 30' and 31 of transformer 32, rectifier 29, resistance 25 to the cathode of tube 42 and across its space path to the anode. The resistance 25 is included in the input and space current circuits of tube 42. The secondary winding of transformer 45 is connected to the loud speaking receiver 50.

The cathodes of the tubes 21, 36 and 42 are connected to a common lead extending to ground at 46.

The tubes 21, 36 and 42 comprise heating elements or filaments 23, 47 and 48 respectively, which are connected in parallel to a secondary winding 33 of transformer 32. The primary winding 49 of this transformer is shown connected to a source 55 of alternating current. This represents any desired source of current and may be an ordinary house lighting circuit supplying sixty cycle current at commercial voltages. In this case the terminals of the primary winding of transformer 32 would be connected to a terminal plug adapted to cooperate with the particular type of outlet socket available. Condensers 51 and 52 are connected in series with each other and in shunt to the filaments of the tubes. The adjacent plates of these condensers are connected by lead 53 to the cathodes of the tubes.

The path between the cathodes and filaments of the tubes including the condensers 51 and 52 is provided to prevent the alternating current flowing in the heating filaments of the tubes from introducing ripples in the space current supplied to the tubes which would tend to cause interference with signals.

The filter 24 comprises a shunt capacity element 24' and a series resistance element 24a. Filter 43 comprises a shunt capacity element 43' and a series resistance element 43a. Resistance 25, is shunted by a condenser 25' which provides a low impedance path in parallel to the resistance 75

for alternating current components. The filter 24 is arranged to prevent any residue of the variable current component flowing in resistance 25 from producing variations in the potential applied to the grid of tube 21. Filter 43 serves a similar purpose with respect to potentials applied to the grid of tube 42.

The small condenser 14 is provided to compensate for the inherent capacity between the grid and anode of tube 21 to thereby prevent the production of parasitic oscillations caused by the transfer of energy from the output circuit of the tube to its input circuit through the tube capacity. The proper degree of compensation may be secured by adjustment of condenser 14. An advantage obtained by the use of this condenser is that of increased amplifying power without causing singing in the tube circuits or distortion of signals.

20 Suitable average polarizing potentials are supplied to the grids of tubes 21 and 42 by the drop of potential caused by the flow of space current through resistance 25.

A suitable average potential is obtained for and impressed upon the grid of tube 36 by the well-known action of the blocking condenser 34 shunted by the leak resistance 35.

Condensers 27 and 38 provide low impedance paths for alternating current associated with the tubes 21 and 36, respectively. They are in shunt to the source supplying space current thereto. The condenser 39 provides a low impedance path about the primary winding of low frequency transformer 37 for any high frequency current component present in the output circuit of tube 36.

In Fig. 2 there is illustrated a connection between the filaments and cathodes of the space discharge tubes of the system which may be substituted for that shown in Fig. 1. This connection provides a low impedance path for alternating current of the frequency of the energizing source. In this arrangement the lead 53, connecting the mid-point of the secondary winding 33 of transformer 32 to the electron emitting cathodes of the tubes, includes a condenser 51a. This connection may be incorporated into the circuit of Fig. 1 by substituting the corresponding elements of Fig. 2 therein and by omitting the condensers 51 and 52 of Fig. 1.

50 The construction of the tubes 21, 36 and 42 used in Fig. 1 is illustrated in detail in Figs. 3, 3a and 4.

As illustrated in Fig. 3 and more clearly shown in Fig. 3a the tube structure comprises a plurality of electrodes including an anode 60, a control electrode 61, an electron emitting cathode 62 and filament or heating element 63 as already enumerated. The relative positions of these elements will be understood by reference to Fig. 3a which is a view in section on line 3a—3a of Fig. 3.

60 The various electrodes of the tube are insulated from each other and supported by individual members 64, 65, 66 and 67 which are in turn supported by the standards 68 and 69 extending vertically from the stem 70.

The stem and standards are constructed of insulating material preferably of glass and made integral with each other and with the envelope or bulb 71. The bulb completely encloses the electrodes and the standards 68 and 69, and is exhausted to a high degree.

65 The anode, control electrode, electron emitting cathode and filament are provided with lead-in conductors 72, 73, 74 and 75, respectively, which pass through the lower wall of the envelope 71.

or through the stem 70. The ends of these conductors are attached to external terminals 76, mounted on the base of the tube. This base includes an insulating disc 77 held in position by a cylindrical collar 78. The base is attached to the bulb 71 in the usual manner.

The tube is adapted to fit into a tube socket having contacts with which the terminals 76 respectively engage.

A getter 79, supported by standard 69 extends above the electrodes of the tube within the envelope 71 and terminates in a circular ring 80 having a narrow ribbon of magnesium wound thereon.

In Fig. 4 there is shown a tube structure which 15 differs from that illustrated in Fig. 3. In this construction the standards comprise vertical wires 68' and 69' having their lower ends sealed in the stem 70 of the tube.

The upper ends of the wires 68' and 69' are 20 attached to and support a bridge 81 of insulating material by which in turn the grid 61, the electron emitting cathode 62 and heating filament 63 are supported and insulated from each other.

The anode or plate 60 is held in position by horizontal wires 68' attached to the standard 68' and 25 69'. The lower end of the standard 68' passes through the stem 70 and serves as a lead-in conductor for the anode. The getter 79 is attached to the upper end of the standard 68'. In other 30 respects the arrangement of this tube is similar to that of Figs. 3 and 3a.

The electron emitting cathode 62 consists of a cylinder of nickel coated on its outer surface with a thermionically active material such as, for example, a mixture of the oxides of barium and strontium. This cathode is positioned within the control electrode 61 and coaxially therewith. Centrally within the cathode 62 is positioned the heating filament 63 which consists preferably of 40 a U-shaped wire of tungsten.

The operation of the system shown in Fig. 1 is as follows: When signal modulated waves are received by antenna 10, which may be tuned to the frequency thereof by adjusting condenser 11, 45 corresponding oscillatory currents are established in the resonant circuit formed by the secondary winding of transformer 13 in cooperation with the condenser 15, it being assumed that this circuit is tuned to the frequency of received 50 waves.

The amplifier 20 operates to produce in its output circuit, amplified currents which correspond in frequency to the waves received by antenna 10. These currents flow through the primary winding 55 of transformer 26 to produce corresponding potential variations in the secondary winding and these are supplied to the grid of tube 36.

By virtue of the well-known action of detector 36, demodulation occurs and currents of signal 60 frequency are produced in the output circuit of this tube. These currents flow through the primary winding of transformer 37 and induce corresponding potentials in its secondary winding which are supplied to the control electrode of 65 tube 42.

The low frequency signal waves are amplified by tube 42 in a manner now well understood and supplied through transformer 45 to the loud speaking receiver 50. The diaphragm of this receiver being vibrated in accordance with the signal currents supplied to it produces sound waves corresponding to the signals.

By virtue of the large surface of the cathodes of tubes 21, 36 and 42 the internal impedance of 75

the tubes is made so small that the efficiency thereof as amplifiers is greatly increased. Because of this fact the number of tubes required for a given degree of amplification is greatly reduced.

As has already been explained a balanced path between the electron emitting cathodes and heating filaments of the tubes is provided by condensers 51 and 52. This path prevents variations corresponding to the frequency of the source of alternating current connected to the primary winding of transformer 32 from affecting the space current flowing through the tube. A new result is thereby produced, in that alternating current may be utilized and the attendant advantages gained while at the same time ripples are eliminated from the system. This may be explained by the fact that any change in the potential gradient, between the cathodes and anodes of the tubes which is produced by a change in the drop of potential along one-half of each filament, will be opposed by a similar change, simultaneously produced by variations in the drop of potential along the other half of each filament, whereby their effects will be neutralized.

The construction of the radio frequency transformer and its operation in the circuit described above to secure uniformity of transmission over a wide range of wave lengths will now be described.

Referring to Fig. 5 the transformer windings 106, 107 and 108 are illustrated partly in section to show the manner of winding. These coils are disc-shaped and have an inner and outer diameter and a depth of winding, all of which are large compared with the width of the winding. In practice these dimensions may be conveniently determined by accurately cutting grooves having these dimensions into a block or spool of suitable material, such as hard rubber or wood, and winding the coils in the grooves. The outline of this spool is indicated at 109.

It has been found that when coils are wound in this manner, are coaxially arranged in parallel planes, are constructed with dimensions included within certain limits and with the proper circuit connections, the transmission characteristic of a receiving set, such as shown in Fig. 1, will in general be represented by the well-known double humped curve of coupled circuits.

It has been found that, as the dimensions of these transformer windings and their separation are varied, the transmission characteristic of the set varies markedly. It has also been found that, as the two coils are brought nearer to each other, the two humps of the characteristic are separated further apart.

Referring to Fig. 6 the curve a—c represents a measured characteristic plotted, between the wave length and voltage amplification of a two-winding coil. For example such as the coil 107—108 when it is connected into the circuit in the manner in which it is used in Fig. 1, but without having associated with it the extra winding 106.

When the extra winding 106, which is open-circuited and not connected to any portion of the circuit, is associated with the windings 107 and 108, a suitable dimension of the coils and a suitable spacing between them being observed, the characteristic of the transformer as a whole is changed from the characteristic curve a—c to the curve a—b.

As a result of measuring a large number of two-windings radio frequency transformers, it

has been observed that there is a marked tendency for the peak of the characteristic occurring at the longer wave lengths to be much more pronounced than the peak occurring at the shorter wave lengths. But by employing an extra winding, such as 106, in connection with the windings that are connected into the circuit, the transmission may be greatly reduced in the region of the long wave length peak as is indicated by the curve a—b.

It will be observed by comparing the curve that the effect of the extra winding is not only to prevent the amplification rising to such a high value in the long wave length region, but it also operates to raise the amplification at each side of the peak portion by producing two minor peaks which are spread over a greater wave length range than the single prominent peak of the characteristic a—c. As a result, a characteristic a—b is obtained which not only gives a more uniform transmission than the curve a—c but also gives high transmission for longer wave lengths than in the case of the characteristic a—c.

The coils of the transformer preferably should have an internal diameter of one inch or greater, a winding depth of the order of one-half inch or more, a width of winding at least as small as one-eighth of the depth of the winding, and a separation between the windings of the order of one-quarter of an inch or less. These dimensions may be varied considerably from the values here given so long as the relative proportions stated are approximately adhered to. Each winding has a terminal connected to its inner layer and a terminal connected to the outer layer. In connecting this coil into the circuit, either the inner layer of the primary is connected to the plate of the tube 21 and the outer layer of the secondary is connected to the grid of the tube 36 (the other terminals being connected through the necessary apparatus or other filaments to the filament circuit), or the outer primary terminal is connected to the plate and the inner secondary terminal is connected to the grid.

As an illustration of the dimensions of the transformers which have proved advantageous in a particular case, it may be stated by way of example, that in the particular case the transformer consisted of two similar windings each having an inner diameter of one and one-quarter inches, a width of winding of three-sixty fourths of an inch and a spacing between the primary and secondary winding of one-eighth of an inch. Each of the connected windings comprising 200 turns of No. 36 Brown and Sharpe gauge double silk-covered copper wire, and an extra open-circuited winding comprising 430 turns of the same-sized wire wound in a groove of the same diameter, and three-thirty seconds of an inch wide, and spaced one inch from the primary transformer winding.

From the preceding description it will be apparent that the present invention provides an electric wave signaling system in which signals may be faithfully reproduced with exceptionally great volume. This is effected, in part, by using space discharge tubes including equipotential cathodes for high frequency amplification, detection and low frequency amplification and an alternating current source for supplying heating current to the cathode heaters and space current to the tubes, as well as polarizing potentials to the control electrodes of amplifiers, with the source so connected that distortion of and interference with the signals is prevented.

The overall efficiency and flexibility of the system is materially increased by using a high frequency transformer having a high transmission efficiency over a relatively broad range of 5 frequencies or wave lengths. Another contribution to the efficiency of the system is obtained by using tubes of simple and rugged construction possessing relatively great electron emissivity.

A further advantage of the system resides in 10 the fact that the number of tubes required to operate loud speaking devices is reduced to a minimum and, in the fact that, by using the ordinary commercial house lighting system as a supply source for the tubes, the use of expensive 15 batteries ordinarily required is avoided. Thus a compact and efficient loud speaking system, which is especially economical as to first cost and cost of operation, is provided.

Although the invention has been illustrated and 20 described in connection with certain specific embodiments, it is intended to be limited only by the scope of the appended claims.

What is claimed is:

1. In a radiant energy signaling system, a plurality 25 of space discharge tubes, said tubes each having an anode, cathode, control electrode and cathode heating element, input circuits connected to said cathodes and control electrodes, output circuits connected to said cathodes and anodes, and means for supplying from a common source of 30 alternating current, suitable average potentials for said control electrodes, space current for said output circuits and heating current to said heating elements, said means including capacitive reactance in the heating current path for 35 preventing variations in said source from affecting the flow of current in said output circuits.

2. In a radio receiving system, a plurality of space discharge tubes coupled in tandem, said 40 tubes having a plurality of electrodes including a cathode and a filament, said cathode having a uniform potential, a source of alternating current for heating said filaments and means comprising a pair of series condensers connected in shunt to 45 said filaments, and a connection between said cathode and the mid-point of said condensers for preventing said source from introducing variations in the potential along said cathode.

3. In a radio receiving system, a plurality of 50 space discharge tubes coupled in tandem, said tubes each having a plurality of electrodes including a cathode and a filament, said cathode having a uniform potential over its surface, a single source of alternating current supplying 55 energy to said tubes including heating current to said filament, and means including capacitively reactive path connected in shunt to said filaments and a connection from the mid-point of said path to said cathodes for preventing variations of current from said source from changing the distribution of potential over the surfaces of 60 said cathodes.

4. In a radio receiving system, a plurality of space discharge tubes coupled in tandem, said 65 tubes each having a plurality of electrodes including a cathode and a filament, said cathode having a uniform potential over its surface, a single source of alternating current supplying energy to said tubes including heating current to 70 said filament, and means including series condensers connected to said cathodes and filaments for preventing variations of current from said source from changing the distribution of potential over the surface of said cathodes.

5. In a radio receiving system comprising a

plurality of plural-electrode space discharge tubes, input output and filament circuits for said tubes, a common alternating current source for said circuits, means common to said input circuits and connected to said output circuits for applying suitable average voltages between the input electrodes of said tubes and filters individual to said input circuits for preventing variations in the current of said source from producing variations in said voltages.

6. In a radio receiving system, a source of alternating current, a rectifier connected to said source, a plurality of space discharge tubes in cascade connection supplied with current from 10 said rectifier, each tube comprising a cathode, anode, control electrode and filament, means traversed by current from said rectifier for applying a potential to said control electrodes, and means comprising frequency selective networks 15 individual to said tubes for preventing variations in the current supplied by said rectifier from causing variations in said potential, each of said networks comprising a shunt arm and a series arm.

7. The combination with an electric space discharge tube having therein an anode, a cathode, a filament for heating said cathode, and a control element, of means for supplying energy to said tube, comprising an alternating current source, a rectifier, a transformer for coupling said source to said tube, said transformer having a winding for supplying current through said rectifier to the space path of said tube and polarizing potential to its control electrode, a winding for supplying current to heat said filament, and a 35 reactance associated with said last mentioned winding to prevent variations in said source from causing ripples in the space current.

8. A high frequency receiving system comprising a high frequency amplifier, a detector and a 40 low frequency amplifier, each of said three devices including a thermionic electrode and a plurality of spaced electrodes, a common heating circuit comprising means for heating said thermionic electrodes, an alternating current source supplying 45 energizing potentials to said plurality of electrodes and to said means, and means comprising a condenser connecting said heating means to said thermionic electrodes, said heating circuit having no metallic electrical connection with any 50 of said electrodes.

9. In a radio receiving system, a high frequency space discharge tube amplifier, a space discharge tube detector adapted to detect and amplify signal waves delivered by said high frequency amplifier, a low frequency space discharge tube amplifier fed from said detector, means for supplying, from a common source of alternating current, control electrode biasing voltages to said amplifiers and all necessary heating currents and plate voltages to said amplifiers and said detector, and frequency selective networks individual to the control electrodes of said amplifiers for preventing said source from producing ripples in the control electrode biasing 60 voltages, each of said networks comprising a shunt arm and a series arm.

10. The combination with a space discharge vessel comprising an anode, a cathode and cathode heating means, of means for supplying alternating heating current to said heating means, means for supplying anode potential to said anode, and means external to said vessel for preventing the heating current in said heating means from causing variation of the average volt- 70

age between the cathode and the anode during a half cycle of said alternating current.

11. The combination with a space discharge vessel comprising an anode, a cathode, and cathode heating means, of means for supplying to said heating means heating current subject to variation, means for supplying anode potential to said anode, and means external to said vessel, for preventing increase occurring in the heating current in said heating means from causing variation of the average voltage between the anode and the cathode during said increase.

12. In a radiant energy signaling system, the combination set forth in claim 1 in which the heating current source is equipped with a mid-point connection and in which the means including capacitive reactance in the heating current path comprises a condenser connected between the cathodes and the mid-point connection.

13. In a signaling system a plurality of electronic relays connected together in cascade and comprising a high frequency amplifier, a detector and a low frequency amplifier, the low frequency amplifier relay having a grid and plate associated with its input and output circuits; a source of rectified alternating current for energizing said high frequency amplifiers and said output circuit, filter means for minimizing fluctuations in the current supplied from said source, said filter means including reactive elements, an impedance having resistance and capacity in series and a separate resistance in shunt with the negative lead from said source between some of the filter elements and said source, and a connection between said input circuit and the end of said impedance adjacent said source whereby the grid of said low frequency amplifier is rendered negative.

14. In combination, a thermionic device comprising an anode, an electron emitter and a control element, heating means associated with, but spaced from, said electron emitter, a transformer connected to said heating means, an impedance connected to a point on said transformer, the average potential of said point being constant with reference to the terminals of said transformer and means for connecting said electron emitter to said impedance.

15. In a vacuum tube circuit, the combination of a tubular plate, a tubular grid within said plate, a cathode within said grid, a resistance element insulatingly mounted within said cathode for heating said cathode, a transformer comprising a primary coil adapted to be arranged in series with a source of alternating current and a secondary coil, said secondary coil being in series with said resistance element, and an electrical conductor capable of transmitting electrical variations joining substantially the mid-point of said secondary coil to said cathode.

16. In a vacuum tube circuit, the combination of a tubular plate, a tubular grid within said plate, a cathode within said grid, a resistance element extending into said cathode but insulated therefrom for heating said cathode, a transformer comprising a primary coil adapted to be arranged in series with a source of alternating current and a secondary coil, said secondary coil being in series with said resistance element, an electrical conductor capable of passing variable currents joining substantially the mid-point of said secondary coil to said cathode, and means for grounding the said electrical conductor.

17. In a vacuum tube circuit, the combination of a tubular plate, a tubular grid within said plate, a tubular cathode within said grid, a resistance element out of electrical contact with said cathode but within said cathode for heating it, a transformer comprising a primary coil adapted to be arranged in series with a source of alternating current and a secondary coil, said secondary coil being in series with said resistance element, and an electrical conductor of low impedance to variable currents joining substantially the mid-point of said secondary coil to one end of said cathode.

18. In a vacuum tube circuit, the combination of a tubular plate, a grid within said plate, a tubular cathode within said grid, a looped resistance element within said cathode but out of electrical engagement therewith for heating said cathode, a transformer comprising a primary coil adapted to be arranged in series with a source of alternating current and a secondary coil, said secondary coil being in series with said resistance element, said source of alternating current tending to produce disturbing components in the plate circuit of said tube and an electrical conductor joining substantially the mid-point of said secondary coil to said cathode, said conductor being such as to transmit currents necessary to reduce the intensity of said disturbing components.

19. In a vacuum tube circuit, the combination of a plate, a grid within the plate, a tubular cathode extending into said grid, a resistance element out of electrical engagement with said cathode but extending therein to render said cathode electronically active, a transformer having its primary connected to a source of alternating current and its secondary connected in circuit with said resistance element, and circuit connections connecting said apparatus in a balanced circuit to balance out the disturbing effects of the current passing through said element.

20. In a vacuum tube circuit, the combination of a plate, a grid within the plate, a tubular cathode extending into said grid, a resistance element out of electrical engagement with said cathode but extending therein to render said cathode electronically active, a transformer having its primary connected to a source of alternating current and its secondary connected in circuit with said resistance element, and circuit connections connecting said secondary and said tube elements in a balanced circuit to balance out the disturbing effects of the current passing through said resistance element.

21. In a vacuum tube circuit, the combination of a tubular electron emitter, a resistance element out of electrical engagement with said tubular electron emitter for rendering the same active, a transformer having a primary connected to a source of alternating current and a secondary connected to said resistance element, and circuit connections connecting said secondary and said electron emitter in a balanced circuit to render ineffective the inductive effect of the alternating current passing through said resistance element.

22. In a vacuum tube circuit, the combination of a tubular plate, a grid within said plate, a tubular cathode within said grid, a looped resistance element out of electrical engagement with said cathode but within said cathode for heating said cathode, a source of varying heating current connected to said resistance element for supply-

- ing heating current thereto, and an electrical connection between said cathode and a portion of said source the average potential of which is constant with reference to the terminals of said source.
- 5 23. In a vacuum tube circuit, the combination of a plate, a grid, a cathode, a resistance element out of electrical engagement with said cathode for heating said cathode, a transformer having a primary winding for connection to a source of 10 alternating current and a secondary winding in series with said resistance element, and an electrical connection between said cathode and substantially the mid-point of said secondary winding.
- 15 24. In a vacuum tube circuit, the combination of a plate, a grid, a cathode, a resistance element out of electrical engagement with said cathode for heating said cathode, a transformer having a primary winding for connection to a source of 20 alternating current and a secondary winding in series with said resistance element, and an electrical connection of low impedance for waves of disturbing frequencies derived from said source between said cathode and substantially the mid- 25 point of said secondary winding.
25. In a vacuum tube circuit, the combination of a plate, a grid, a cathode, a heater for said cathode, means for supplying varying current to said heater for heating said cathode, and an 30 electrical connection between said cathode and a point on said means, the average potential of which is substantially constant with reference to the terminals of said means.
26. A plurality of thermionic devices connected 35 in cascade and having anodes and cathodes, a power supply means therefor including a source of alternating current, a rectifier, and filtering means for the rectified current constructed to filter the anode current to one of said devices 40 more effectively than the anode current to another of said devices.
27. A plurality of thermionic devices connected 45 in cascade and having anodes and cathodes, one of said devices being connected and suitably energized to detect modulated high frequency carrier currents and another of said devices being more powerful and more powerfully energized than said first device and connected to amplify the currents of modulation detected by said first de- 50 vice, a power supply means for said devices including a source of alternating current, a rectifier, and filtering means for the rectified current constructed to filter the anode current to said detecting device more effectively than the 55 anode current to said amplifying device.
28. A plurality of thermionic devices connected 60 in cascade and having anodes and cathodes, a power supply means therefor including a source of alternating current, a rectifier, and filtering means for the rectified current constructed to filter the anode current to one of said devices more effectively than the anode current to another of said devices, said filtering means being substantially free from current drain other than that 65 required for the anode currents of the thermionic devices of said cascade.
29. A plurality of thermionic devices connected 70 in cascade and having anodes and cathodes, one of said devices being connected and suitably energized to detect modulated high frequency carrier currents and another of said devices being more powerful and more powerfully energized than said first device and connected to amplify 75 the currents of modulation detected by said first

device, a power supply means for said devices including a source of alternating current, a rectifier, and filtering means for the rectified current constructed to filter the anode current to said detecting device more effectively than the anode 5 current to said amplifying device, said filtering means being substantially free from current drain other than that required for the anode currents of the thermionic devices of said cascade.

30. A radio receiver having an audio amplifier 10 tube, an electric circuit and a source of electrical energy for energizing the anode thereof, said circuit comprising filtering condensers and inductances and an ohmic resistor in circuit with 15 said inductances and disposed in the return side of said circuit, a connection at one end of said resistor for biasing the grid in said tube, a second resistor in said connection, a condenser connected to the second resistor, and to the filament 20 circuit of said tube, and a ground connection between said second condenser and said filament circuit, said second condenser and last-named resistor forming a circuit to filter out alternating 25 current oscillations from the connection between said resistors and the grid.

31. In a vacuum tube circuit, the combination of a tubular plate, a grid within said plate, a tubular cathode within said grid, a looped resistance element within said cathode but out of electrical engagement therewith for heating said cathode, a transformer comprising a primary coil adapted to be arranged in series with a source of alternating current and a secondary coil, said secondary coil being in series 30 with said resistance element, and an electrical connection joining substantially the midpoint of said secondary coil to said cathode.

32. In a vacuum tube circuit, the combination of a tubular plate, a tubular grid within said plate, a cathode within said grid, a resistance element insulatingly mounted within said cathode for heating said cathode, a transformer comprising a primary coil adapted to be arranged in series with a source of alternating current and a secondary coil, said secondary coil being in series 45 with said resistance element, and means for conducting the flow of disturbing currents, joining substantially the midpoint of said secondary coil to said cathode.

33. In a vacuum tube circuit, the combination 50 of a tubular plate, a tubular grid within said plate, a cathode within said grid, a resistance element extending into said cathode but insulated therefrom for heating said cathode, a transformer comprising a primary coil adapted to be arranged in series with a source of alternating current and a secondary coil, said secondary coil being in series with said resistance element, a lead for variable currents joining substantially 55 the midpoint of said secondary coil to said cathode, and means for grounding the said lead.

34. In a vacuum tube circuit, the combination of a tubular plate, a tubular grid within said plate, a tubular cathode within said grid, a resistance element out of electrical contact with said cathode but within said cathode for heating it, a transformer comprising a primary coil adapted to be connected to a source of alternating current and a secondary coil, said secondary coil being in series with said resistance element, and a connection for conducting current variations joining substantially the midpoint of said secondary coil to one end of said cathode.

35. In a vacuum tube circuit, the combination 75

of a tubular plate, a grid within said plate, a tubular cathode within said grid, a looped resistance element within said cathode but out of electrical engagement therewith for heating said cathode, a transformer comprising a primary coil adapted to be arranged in series with a source of

alternating current and a secondary coil, said secondary coil being in series with said resistance element, and means including a wire joining substantially the mid-point of said secondary coil to said cathode.

SIDNEY E. ANDERSON.
